AIRPLANE

Kenneth J. Watson, 4 Hazelwood Lane, Hazelwood, Mo.

Filed June 19, 1964, Ser. No. 80,478

Term of patent 14 years

(Cl. D71—1)

FIG. 1 is a top plan view of an airplane showing my new design;

FIG. 2 is a bottom plan view thereof;

FIG. 3 is a front elevational view thereof;

FIG. 4 is a rear elevational view thereof; and

FIG. 5 is a side elevational view thereof, the opposite side being a mirror image.

The dominant features of my design reside in the portions shown in full lines; said broken lines being omitted from FIGS. 2 through 5 for convenience of illustration.

I claim:

The ornamental design for an airplane, as shown and described.
